UNITED STATES PATENT OFFICE.

FRANK A. GRITT AND ARTHUR E. GRITT, OF INDIANAPOLIS, INDIANA.

ADVERTISING DEVICE.

Application filed March 17, 1922. Serial No. 544,555.

To all whom it may concern:

Be it known that we, FRANK A. GRITT and ARTHUR E. GRITT, citizens of the United States, and residents of Indianapolis, county 5 of Marion, and State of Indiana, have invented a certain new and useful Advertising Device; and we do hereby declare that the following is a full, clear, and exact description thereof, reference being had to the accompanying drawings, in which like numerals refer to like parts.

This invention relates primarily to a unitary advertising device, although several elements thereof may be otherwise utilized.

15 The chief object of this invention is to provide a construction wherein a blaze or wave motion effect is secured without the use of inflammable material, thereby eliminating the danger of fire.

20 The chief feature of the invention consists in the association of a rotary reflecting screen with a source of illumination, which source of illumination is adapted to rotate said screen.

25 Another feature of the invention consists in the rotation of the advertising device by the illumination means.

The full nature of this invention will be understood from the accompanying drawing 30 and the following description and claim.

In the drawings Fig. 1 is a perspective view of the advertising device as a unit. Fig. 2 is an enlarged central sectional view 35 of the advertising device. Fig. 3 is a top plan view of the same. Fig. 4 is a developed view of the rotary reflecting screen.

40 In the drawings 10 indicates any suitable support and the angular bracket 11 is secured to said support by suitable means, such as the chain 12. The angular bracket 11 has an upwardly extending portion 13 which provides a central axis and said extension 13 is in alignment with the chain 45 support 12. The extension 13 terminates in a lamp socket 14 which carries a lamp bulb 15. Current is supplied to the lamp bulb 15 through the socket 14 by means of the current conducting wires preferably positioned in the tubular support 11 and are herein not shown.

Herein there is illustrated a standard 16 which is suitably supported upon the support 11 near the base thereof and is provided with an angular portion which terminates in a point 17, said point being in axial

alignment with the axial extension 13. A frame-work consisting of a plurality of face forming frames 18 forms a hollow and tubular construction, the bottom of which is open 60 and the top of which is closed by the plate 19 which is suitably apertured at 20 to form a plurality of blades 21 which are positioned angularly of said body portion 19. The central portion of the plate 19 is shaped to 65 form a depression or socket 22 which is adapted to receive the point 17. If desired, a suitable fan construction 23 may be associated with the under side of the top plate 19 and it is to be understood that said fan 70 construction has its blades registering with the blades 21 to form a continuation thereof, although the angle thereof may be changed if desired. In this manner with either of the foregoing constructions, the top 19 forms a 75 propeller or fan device and an axial current of air passing through the openings 20 in the top 19 will rotate said top and the face forming frame work therewith by engaging the blade portions 21.

80 Each of the faces 18 of the hollow tubular frame work may be provided with a transparent or translucent closure 24 which may carry suitable advertising matter. It is, of course, to be understood that the hollow tubular construction may be cylindrical, conical or barrel shape and the like without departing from the broader features of the invention. The broad idea of utilizing a heating current of air which rises into the colder 85 portions of the air for rotational purposes is broadly old and the same per se is not claimed in this invention. The lamp 15 thus supplies illumination to the transparent or translucent material 24 to illuminate the advertising matter therein or thereon, and said lamp also, by means of the column of heated air which rises therefrom, rotates the tubular advertising framework.

90 There is also provided a rotary reflecting screen construction which is positioned within the tubular advertising device hereinbefore described and substantially encloses the source of illumination or lamp bulb 15. Reference will be had to Figs. 2 and 4 where- 100 in the construction of said rotary reflecting screen is illustrated in detail. The rotary reflecting screen comprises a suitable central socket 25 and a pear-shaped body portion 26 which terminates in an open lower end. 105 The body portion 26, as shown clearly in said Figs. 2 and 4 is formed from a plurality of

radiating S-shaped arms, the inner and central ends of which are suitably secured together to form a central support. The outer and free end of each arm is secured to its adjacent neighbors by suitable means, such as the clips or rivets 27. When thus secured there is formed a rotary screen having a plurality of curved openings 28 and an open base. There is also provided a supporting member 29 having a point 30 and a base 31, and herein said supporting member 29 is shown associated with the lamp, although the same may be associated with the socket without departing from the invention. It is to be noted that the point 30 of said supporting member 29 is receivable by the socket 25, whether said socket is rigidly secured to the rotary screen or whether it supports the same, and thus a pivotal support for said rotary screen is provided.

A further feature of the invention consists in providing said rotary screen with an inner surface of reflecting or mirror qualities, whereby the light received by the arm portions 26 will be reflected through the other apertures 28, thereby utilizing all of the light rays either by radiation or by reflection. The construction of the rotary reflecting screen is such that the air heated by the lamp 15 passes upwardly and outwardly from said lamp and rotates said screen in its upward movement. The heated air thereafter passes upwardly in the manner hereinbefore described and rotates the tubular framework.

It will be readily apparent from the foregoing description that the device may be constructed of non-inflammable material, yet

the rotary screen is adapted to simulate a fire or a blaze behind the illuminated translucent or transparent medium. Likewise the rotary screen in its rotation darkens the transparent or translucent medium and thereby simulates a wave effect. It will also be remembered that the transparent medium is rotatably mounted and is rotated, but the device herein illustrated is such that the rates of rotation are not the same and, therefore, there will be an ever changing wave formation, due to the difference in the speeds of rotation.

While the invention has been described in considerable detail in the foregoing specification, said detailed description is to be considered illustrative and not restrictive in character and the many modifications thereof which will readily suggest themselves to those skilled in the art, as well as those hereinbefore suggested, are all considered to be within the purview of this invention, reference being had to the appended claim.

The invention claimed is:

A rotatable screen comprising a plurality of radiating S-shaped arms having their inner ends secured together and their outer ends secured together, the inner ends pivotally supporting the rotary screen and the outer ends forming an opening, each of said arms having an inner reflecting surface, said screen being adapted to enclose a source of illumination.

In witness whereof, we have hereunto affixed our signatures.

FRANK A. GRITT.
ARTHUR E. GRITT.
